UNITED STATES PATENT OFFICE.

GEORGE W. SHERWOOD, OF NEW BRIGHTON, PENNSYLVANIA.

DESIGN FOR A TEA-POT.

SPECIFICATION forming part of Design No. 12,398, dated August 2, 1881.

Application filed January 24, 1881. Term of patent 7 years.

To all whom it may concern:

Be it known that I, GEORGE W. SHERWOOD, of New Brighton, in the county of Beaver and State of Pennsylvania, have invented a new and useful Design for Earthenware Tea-Pots; and I do hereby declare the following to be a full, clear, and exact description thereof, reference being had to the accompanying drawings, forming a part of this specification, in which—

Figure 1 is a sectional view of my design, and Fig. 2 is a side elevation of the same.

Heretofore earthenware and similar tea-pots, though formed with a taper from the base to the lip or top, have been made with flat bottoms, or with rims around the bottom, which obstructed the outlines and gave the article the general form of a truncated cone or pyramid.

My design is produced by giving to the bottom of the pot the form of a hemisphere the outline whereof is unobstructed except at the points where the supporting knobs or feet are attached.

The general outline of the pot when the cover is in place will be oviform; but it is apparent that the leading feature, and the one which gives character to the article, is the hemispherical bottom, the form of the handle and spout being immaterial provided the rules of symmetry are regarded.

I will now proceed to describe the design more fully.

In the drawings, *a* indicates the body of a tea-pot; *b*, the cover or lid; *c*, the spout; *d*, the handle; *e*, the bottom, and *f*, knobs, projections, or feet which support the pot.

The body *a* has the general form of a frustum of a cone, while the bottom *e* is a hemisphere of a diameter equal to the base of the cone.

The spout *c* and handle *d* are preferably formed with curved lines which harmonize with the general design.

The cover or lid *b* is a hemisphere whose diameter approximates the least diameter of the frustum.

The size or form of feet *f* is not material, provided they do not materially obstruct the outlines of the bottom or detract from the general effect. Usually they are tapering or coniform, as shown in the drawings.

Having thus described my invention, what I claim, and desire to secure by Letters Patent, is—

1. A design for tea-pots, consisting of the body thereof in the form of a frustum of a cone, and the bottom in the form of a hemisphere the diameter of which corresponds to that of the base of the cone, the outlines of the bottom being unobstructed, except by the knobs or points of support, substantially as specified.

2. As a design for tea-pots, the oviform configuration consisting of the body of the pot in the form of a frustum of a cone, the bottom in the form of a hemisphere of diameter corresponding to the base of the cone, and the lid in the form of a hemisphere of diameter approximating the least diameter of the frustum, substantially as specified.

In testimony whereof I have hereunto set my hand.

GEORGE W. SHERWOOD.
